US00D652776S

(12) **United States Design Patent**
Agoncillo et al.

(10) **Patent No.:** **US D652,776 S**
(b5) **Date of Patent:** **** Jan. 24, 2012**

(54) **AUTOMATED RETRACTABLE STEP APPARATUS**

(75) Inventors: **Cielito B. Agoncillo**, Newtown, PA (US); **W. Brian McGinty**, Huntingdon Valley, PA (US); **Michael P. Ziaylek**, Yardley, PA (US)

(73) Assignee: **Michael P. Ziaylek**, Yardley, PA (US)

(**) Term: **14 Years**

(21) Appl. No.: **29/349,462**

(22) Filed: **Apr. 6, 2010**

(51) LOC (9) Cl. **12-16**

(52) U.S. Cl. **D12/203**

(58) **Field of Classification Search** D12/203, D12/162; 280/166, 491.3, 491.5, 416.1, 280/497, 163-164.1, 169, 153.5, 848; 224/519, 224/524, 497; 182/90-92; D25/68-69, 62; 428/81-82; 238/14; 187/200-202; 105/444, 105/449; 414/390, 391, 399, 537; 14/71.1, 14/71.3

See application file for complete search history.

(57) **CLAIM**

The ornamental design for an automated retractable step apparatus, as shown and described.

DESCRIPTION

FIG. 1 is a front three-quarter perspective taken from the left embodying our new design;

FIG. 2 is a front plan view;

FIG. 3 is a rear plan view;

FIG. 4 is a side plan view as seen from the left in FIG. 1;

FIG. 5 is a side plan view as seen from the right in FIG. 1;

FIG. 6 is a top plan view; and,

FIG. 7 is a bottom plan view.

The broken lines shown in the drawings represent unclaimed portions of the automated retractable step apparatus and form no part of the claimed design.

1 Claim, 6 Drawing Sheets
